CYLINDER RIDGE REAMER

Carl A. Olson, Clarinda, Iowa, assignor, by mesne assignments, to Lisle Corporation, Clarinda, Iowa, a corporation of Iowa

Application May 11, 1931. Serial No. 536,522

5 Claims. (Cl. 77—76)

The object of this invention is to provide an improved construction for a tool for easily, quickly and accurately removing a ridge or ledge from a cylinder whereby the walls of the cylinder may be uniform in contour throughout their length.

5 A further object of the invention is to provide an improved cylinder reamer especially designed for use in trimming off a ledge or projection formed at the upper end of the cylinder of an 10 internal combustion engine because of the fact that the uppermost piston ring does not travel entirely to the top of the cylinder bore and the wear from ordinary usage consequently does not extend entirely to the top.

15 Still another object is to provide a cylinder ridge reamer which is capable of being expanded for operation on cylinders of various diameters and which is so arranged that the expansion takes place uniformly on radial lines.

20 Another and further object of the invention is to provide improved means for adjustment of the cutting tool and of the stop means for terminating the operation of the tool in conformity with the contour of the worn portions of the cylinder 25 wall.

With these and other objects in view my invention consists in the construction, arrangement and combination of the various parts of my device, whereby the objects contemplated are attained, as hereinafter more fully set forth, pointed out in my claims, and illustrated in the accompanying drawing, in which:

Figure 1 is a perspective view of my improved cylinder ridge reamer.

35 Figure 2 is a vertical section of the same on the line 2—2 of Figure 1, and illustrating the tool in position for use.

Figure 3 is a horizontal section on the line 3—3 of Figure 2.

40 Figure 4 is a sectional view showing a piston in its cylinder and illustrating the condition which my improved tool is designed to relieve.

The wear on the wall of a cylinder such as 10 is not usually uniform in a direction circumferentially of the cylinder wall, nor in a direction longitudinally of the bore. The piston 12 in its travel often causes the cylinder wall to be worn to an "out of round" condition and furthermore a ridge or ledge such as 14 is left at the top of 45 the cylinder bore because of the fact that the uppermost piston ring 16, which is expanded resiliently against the cylinder wall, does not travel entirely to the top of the bore.

Before installing a new piston in a cylinder or 55 new rings on an old piston, it is necessary to remove the ledge or ridge 14 in order that the piston and its rings may be properly fitted and in order to avoid any click or knock which would be occasioned by engagement of the new ring 16 with 60 the ledge.

The ordinary method of removing the ledge or ridge such as 14 has been by the use of a hand tool or by rubbing with abrasive material. This is slow work and furthermore, it is difficult by such a method to make the upper end of the cylinder bore conform to the remaining portions of the cylinder wall because, for one thing, the cylinder wall is not always worn to true cylindrical form.

70 My new tool is designed for easily and quickly removing the ridge or ledge 14 and causing the upper portion of the cylinder wall to conform to the curvature of the remaining portions, or in other words, those portions which have been worn by travel of the piston and its rings.

75 The body of the tool includes a top plate 18 and a bottom plate 20 which are of substantially conical form and arranged with their points directed toward each other and variably spaced apart. For adjustably connecting the plates 18 and 20 I employ a series of rods 22, in this instance three in number, which are fixed at their upper ends to the top plate 18 and which pass slidably through the plate 20.

80 A series of carriers are movably mounted between the head plate 18 and base plate 20 and are formed tapering at their ends for engagement with the opposed conical surfaces of said plates. Two of the carrier members are alike in construction and are designated by the numerals 24 and 85 26, but the other carrier member 28 is slightly different. Each carrier member is formed at its 90 upper end with a reduced tongue 30 engaging slidably in a groove 32 in the lower surface of the top plate 18 and each carrier is formed at its lower end with a tongue 34 engaging in a groove 36 in the upper surface of the bottom plate. It will be observed that these tongue and groove 95 connections are on inclined lines relative to the axis of the device and that this permits an expansion and contraction of the carriers relative to the conical top and bottom plates by radial outward and inward movement.

100 The head plate 18 and bottom plate 20 are further connected by a screw headed bolt 38 upon the threaded lower end of which is mounted a nut 40. The head of the bolt 38 is located in an angular recess 42 opening to the top of the plate 18, and this recess is adapted to receive a suitable tool such as 44 by means of which the device 105 may be manually rotated.

110 In the lower surface of the bottom plate 20 is formed an angular recess 46 adapted to snugly receive the nut 40 and prevent rotary movement thereof. An expansion spring 48 is mounted on the bolt 38 within the recess 46 and behind the nut 40. If desired, a pin 50 may be mounted through the lower end of the bolt to prevent accidental removal of the nut 40.

115 The carrier members 24 and 26 are formed with outwardly opening recesses 52 within which rollers 120

54 are rotatably mounted on vertically extending pins 56. The rollers 54 are adapted to travel in contact with the walls of the cylinder 10 during the operation of the tool, and said rollers are formed at their upper ends with flanges 58 adapted to travel on the engine block at the upper periphery of the cylinder bore. Each roller 54 is formed below the flange 58 with a peripheral groove 59 which is designed to straddle or embrace the ledge or ridge 14 at the top of the cylinder.

10 The other carrier member 28 is formed with a smaller laterally opening recess 60 within which a roller 62 is journaled on a vertically extending pin 64. The roller 62 is adapted to travel entirely within the cylinder and in contact with its wall.

15 The carrier member 28 is also formed in its outer face with an angular recess 66 in which a cutter blade 68 is mounted, said blade being backed by an expansive spring 70 mounted in the inner end of the recess. The spring 70 causes the cutting edge of the blade 68, which is vertically arranged, to be projected slightly beyond the wall of the carrier member.

20 25 A stop member 72 is disposed at the outer side of the carrier member 28 above the cutter blade 68 and is formed of a vertically arranged plate through which a threaded screw 74 is loosely mounted. A laterally opening threaded bore 76 is formed in the carrier member 28 and within this bore is threaded an adjusting screw 78 which is hollow and internally threaded to receive the screw 74. The adjusting screw 78 is adapted to be engaged at its outer end by the stop plate 72 30 when the screw 74 is tightened up. The screw 78 is formed at its outer end with a screw driver slot 80 whereby it may be adjusted in the threaded bore 76.

35 The carrier member 28 is formed with an upwardly opening threaded bore 82 which intersects the bore 76. In the bore 82 is mounted a set screw 84 adapted to engage the hollow adjusting screw 78 and hold it in adjusted position. When the stop plate 72 is drawn up tightly against the outer end of the adjusting screw 78 by means of the screw 74 it forms a positive stop means which is adjustable and yet is held rigidly in any selected position of adjustment.

40 45 The stop plate 72 overlaps at its lower end the upper edge of the cutting blade 68 and serves to limit outward movement of the blade under the influence of the spring 70.

50 55 The hollow adjusting screw 78 is set in such position that its outer end is in vertical alignment with the periphery of the roller 62 and is held in such adjustment by the set screw 84. The position of the screw 78 is not ordinarily disturbed except to compensate for wear and it thus serves to govern the position of the inner face of the stop plate 72 in line with the roller 62 for forming a stop for the cutting blade 68, which will conform to the position of said roller.

60 65 The carrier members 24, 26 and 28 are yieldingly held in position with respect to the head plate 18 and bottom plate 20 by means of a pair of endless coil springs 86 and 88 encircling said carrier members and preferably mounted in transverse grooves 90 formed in their outer faces.

70 75 In practical use the tool is placed in position within the upper end of the bore of a cylinder and a screw driver or the like is employed for expanding the tool by tightening the bolt 38, it being understood that the nut 40 on said bolt is held against rotation by engagement in the recess 46. The tightening of the bolt 38 causes the

80 plates 18 and 20 to be drawn toward each other, thereby forcing the tapered carrier members 24, 26 and 28 outwardly in their seats against the action of the springs 86 and 88.

85 This tightening action is continued until the peripheries of the rollers 54 and 62 engage the inner wall of the cylinder and then is continued somewhat past that point, thereby relieving the tension on the springs 86 and 88 and placing the spring 48 under tension.

90 95 The tool is supported with respect to the cylinder 10 by means of the flanges 58 on the rollers 54 and also by the stop plate 72 which engages the top of the cylinder wall. In this position the rollers 54 and 62 are in engagement with the worn portion of the cylinder wall and the point of the cutting blade 68 rests against the ridge or ledge 14 at the upper end of the cylinder and is forced thereagainst by action of the spring 70.

100 105 Rotary oscillation is then imparted to the reamer manually by the use of the wrench or tool 44, thereby causing the blade 68 to cut and ream away the projecting ledge 14. The contact of the rollers 54 and 62 with the inner surface of the cylinder causes the blade 68 to conform to the contour of the cylinder wall so that said blade cuts away the projection 14 in conformity with such contour. Inasmuch as the outer periphery of the roller 62 is in exact vertical line with the inner face of the stop member 72, it follows that this cutting operation will be automatically terminated by contact of the blade with the inner face of said stop member, when the projecting ledge has been cut away to the proper amount to conform exactly with the worn cylinder wall. 110 This is true even though the contour of the worn wall may not be exactly cylindrical, inasmuch as the tension of the spring 48 causes the roller 62 to travel at all times in exact contact with the worn cylinder wall and the spring 70 causes the blade 68 to be thrust outwardly to perform its work. In other words the carrier members 24 and 26 which are provided with the rollers 54 and the carrier member 28 which is provided with the roller 62 and stop 72, are forcibly expanded within the cylinder so that the roller 62 is caused to follow accurately the cylinder wall and to determine the position of the stop member 72 against which the cutting blade 68 is engageable at the limit of the cutting operation.

115 120 125 The reamer is very easily operated by manipulating the wrench or hand tool 44 so that the projecting ledge 14 is easily and quickly cut away and the upper part of the cylinder is caused to conform to the worn part of the wall below it. It will be observed that the angular opening for the tool 44 is always located at the axial center of the reamer because the carrier members for the rollers and cutting blade are radially arranged about the axis of the tool and are caused to move uniformly on radial lines.

130 135 140 While the enlarged flanges 58 on the upper ends of the rollers 54 form a convenient means for supporting the reamer with respect to the cylinder, yet I do not wish to be understood as limiting myself to this particular means inasmuch as equivalent supporting means may be employed if desired.

145 Considerable expansion of the reamer for work on cylinders of different diameter may be obtained because of the tapered formation of the heads 18 and 20 and the carrier members 24, 26 and 28. The inclined tongue and groove connections between these members permits easy slid-

ing movement of the carrier members in expanding and contracting the reamer to the desired diameter.

This tool has been especially designed for use 5 on cylinders of internal combustion engines, but it is obvious that it may be applied in connection with any cylinder that has a similar projecting portion to that indicated by the numeral 14, and I do not desire to be understood as limiting myself to the exact method of use or the particular purpose herein set forth.

I claim as my invention:—

1. A cylinder ridge reamer comprising a pair of spaced slidably connected heads, said heads having oppositely inclined faces on their adjacent sides, a plurality of carrier members having inclined faces contacting with the faces of said heads, resilient means acting to hold said carrier members in place between the heads and tending to move them inwardly whereby said heads are forced apart by mutual engagement of said inclined faces, rollers pivoted on said carrier members, a bolt having a threaded connection for adjustably connecting said heads, a spring means adapted to be placed under compression by tightening movement of said bolt when the carrier members are confined against outward movement, thereby yieldingly forcing said rollers into engagement with the surface of a cylinder within which the reamer is operated, a blade slidably mounted in one of said carrier members, a spring acting to move said blade outwardly for operation on a part of the cylinder wall, and a stop means for limiting outward movement of said blade whereby to limit its cutting operation to conform to the surface engaged by said rollers, said stop means including a hollow screw threaded in the last named carrier member, a stop plate, and a screw for holding said plate 40 against the outer end of said hollow screw.

2. A cylinder ridge reamer comprising a pair of substantially conical heads arranged with their bases away from each other, a plurality of carrier members each having inclined ends 45 in slidable engagement with the conical surfaces of the respective heads and movable on substantially radial lines, rollers pivoted on vertical axes on said carrier members adapted to engage a cylinder wall and travel thereon, a bolt extending 50 adjustably through said heads and having a threaded connection adapted to be tightened for drawing said heads together and thereby forcing the carrier members outwardly, yielding means adapted to be placed under compression 55 by such tightening and tending to force said carrier members and rollers outwardly, stop means carried by one of said carrier members in a position conforming to the periphery of its roller, and a yieldably mounted blade carried 60 by the last named carrier member for engagement with a portion of the cylinder wall and limited in its movement by said stop means, whereby the cutting operation of said blade will be caused to conform to the contour of the surface 65 engaged by said roller.

3. A cylinder ridge reamer comprising a pair of substantially conical heads arranged with their bases away from each other, rods on one of said heads extending slidably through 70 other, a plurality of carrier members each having inclined ends in slidable engagement with the conical surfaces of the respective heads and movable on substantially radial lines, rollers piv-

oted on vertical axes on said carrier members adapted to engage a cylinder wall and travel thereon, a bolt mounted slidably through said heads, a nut having a threaded engagement with said bolt and held against rotation, a spring on said bolt adapted to be placed under compression by tightening movement of the bolt when said carrier members are confined against outward movement, said spring tending to move said rollers outwardly into contact with the cylinder wall, and permitting them to move inwardly under pressure, a blade carried by the last named carrier member for engagement with a portion of the cylinder wall and means to limit the cutting operation of said blade so that the cut will be caused to conform to the contour of the surface engaged by said roller.

4. A cylinder ridge reamer comprising a pair of spaced relatively movable heads having oppositely inclined faces on their adjacent sides, a plurality of carrier members having inclined faces contacting with the faces of said heads, resilient means acting to hold said carrier members in place between the heads and tending to move them inwardly on radial lines, rollers rotatably mounted on said carrier members, a bolt affording an adjustable connection for drawing said heads together and thereby exerting outward pressure on the carrier members, resilient means adapted to be placed under compression by tightening movement of said bolt when the carrier members are confined against outward movement, thereby yieldingly forcing said rollers into engagement with the surface of a cylinder within which the reamer is operated, a blade 110 slidably mounted in one of said carrier members, yielding means acting to move said blade outwardly for operation on a part of the cylinder wall, and stop means for limiting outward movement of said blade whereby to terminate its cutting operation in conformity to the surface engaged by said rollers, said stop means including a hollow screw threaded in the last named carrier member, a part at the outer end of said screw adapted to be engaged by said blade, and screw means for normally preventing rotary movement of said hollow screw.

5. A cylinder ridge reamer comprising a pair of spaced adjustably connected heads, said heads having oppositely inclined faces on their adjacent sides, a plurality of carrier members having inclined faces contacting with the faces of said heads, resilient means acting to hold said carrier members in place between the heads and tending to move them inwardly whereby said heads are forced apart by mutual engagement of said inclined faces, guides on said carrier members, a bolt having a threaded connection for adjustably connecting said heads, spring means adapted to be placed under compression by tightening movement of said bolt when the carrier members are confined against outward movement, thereby yieldingly forcing said guides into engagement with the surface of a cylinder within which the reamer is operated, a blade on one of said carrier members yieldingly forced outwardly for operation on a part of the cylinder wall, and a stop member, the guides, blade and stop member being so constructed and arranged as to limit the cutting operation of the blade to conform to the surface engaged by said guides.
